UNITED STATES PATENT OFFICE.

ROBERT THOMAS MULLINS, OF BROOKLYN, NEW YORK, ASSIGNOR TO A. G. SPALDING & BROS., OF NEW YORK, N. Y., A CORPORATION OF NEW JERSEY.

SHOULDER PAD.

Application filed November 1, 1926. Serial No. 145,453.

The subject of the present invention is an improved body-protector particularly designed for a football player.

The new protector will be designated a shoulder guard; although in the preferred embodiment of the invention illustrated in the accompanying drawings the shoulder guard will also include auxiliary shield or buffer elements, such as breast, back and 10 epaulette sections, for various parts of the torso in the shoulder region as well as bones or joints at or near the junction of upper arm and shoulder.

One of the principal objects of the invention is to provide a shoulder guard which when worn will, in a higher degree than heretofore, combine maximum protection and minimum weight and discomfort.

Another object is to provide a shoulder guard as just described, wherein the different relatively movable sections or portions thereof are so constituted and related as to cause a natural fitting or shaping of the guard to the body of a wearer and at the same time always to insure that the guard will be donned to establish and thereafter maintain adequate protection for the entire anatomical region covered and particularly for parts of the body heretofore inadequately shielded from strain or damage.

Another object is to provide a ribbed protective structure in which the ribs include relatively narrow strips of cushioning material, such as sponge rubber, for the sake of economy by the utilization of such relatively small pieces of the material while at the same time producing a flexible or articulated shell having improved protective qualities.

The characteristics and advantages of the invention are further sufficiently explained in connection with the following detail description of the accompanying drawing, which shows one representative embodiment.

After considering this example, skilled persons will understand that many variations may be made without departing from the principles disclosed, and I contemplate the employment of any structures that are properly within the scope of the appended claims.

In said drawings:

Figure 1 shows a preferred form of the invention in perspective, approximately as the various parts would be arranged on the

body of the player, and as the device would be seen when viewed from a point somewhat above the shoulder looking toward the neck of the wearer;

Figure 2 is a section, taken on line 2—2 of Figure 1; and

Figure 3 is an enlarged sectional view taken on the line 3—3 of Figure 1, but with said line rectified.

The form of the invention thus shown in the drawings includes a central shoulder saddle or main portion 5 having pendent breast and back flaps or sections 6 and 7. Sections 6 and 7 are hingedly suspended, as by the lines of stitching indicated at 8 and 9 in Figure 1; such lines of stitching joining sheets 10, 11 and 12 of leather of a kind and thickness to make the sheets fairly stiff yet rather freely flexible.

The sheets 11 and 12 of the sections 6 and 7 are corrugated longitudinally, that is, substantially parallel with the stitching lines 8 and 9. The corrugations may be different in number on the two sections; presenting four relatively narrow troughs on the breast section 6 and five of such troughs on the back section 7. The leather sheets of said sections are also formed as to present at the upper end of each section a narrow margin of about the width of a trough bottom, and said sheets are also so formed as to present at the lower end of each section a similar margin; as most clearly shown in Figure 1. The upper margins of the sections receive the stitchings 8 and 9. Certain of these stitchings 8 and 9 pass also through narrow margins arranged along the converging forward and rear edges of the sheet 10 of main section 5, as well as through a sheet or pad 14 of felt underlying the three leather sheets and common to all the sections. The margins at the lower ends of the leather sheets 11 and 12 of the breast and back sections are similarly stitched to the felt pad, as indicated at 15 in Figure 3.

The various trough bottoms of the breast and back sections 6 and 7 are also stitched to the felt pad 14, to provide for each of said breast and back sections a plurality of ribs each hinged or articulated relative to an adjoining rib. These ribs result not only from the corrugated formations of the leather sheets 11 and 12 and the lines of

stitching in the troughs aforesaid, but also, in part at least, from the fact that the stitching last referred to also go through the felt pad 14, thus to localize lines of felt-compression subtended by grooves in the felt, opposite the trough bottoms, all as shown clearly in Figures 1 and 3.

At the far ends of said troughs, as the shoulder guard is viewed in Figure 1, eyelets are applied, certain of said eyelets being shown at 4 in Figures 1 and 2, through which lacing may pass to connect two similar shoulder guards together.

The ribs formed by corrugating the leather sheets 11 and 12 as described, are filled with a flexible and resilient material, to cooperate with the flexible and resilient buffer means comprised by the felt pad 14, as well as to hold or aid in holding the ribs normally distended as such. And, in order to make the new shoulder guard of protective value to an opponent as well as to the wearer of the guard, these filler elements 16 for the ribs of the breast and back sections desirably consist of relatively narrow strips of sponge rubber both to provide desirable resiliency or cushioning against impacts and for the sake of economy in manufacture by the utilization of these relatively narrow strips which in some cases may be scrap material cut from larger sheets utilized for other purposes.

Referring to the main portion or section 5, the leather sheet 10 thereof, as most clearly shown in Figure 3, has its major central part elevated above felt pad 14, said part being joined, to the margins through which stitchings 8 and 9 are applied, by upstanding wall portions as shown at 10' in Figure 3. In the wide pocket thus provided by the leather sheet 10 and the felt pad, is fitted a sponge rubber filler 17.

As shown in Figure 2, the central portion of leather sheet 10 has an off-shoulder integral extension 10^a, of a shape such that the curved edge thereof conforms to and will be matched with the curved edge of the projecting portion of a protective epaulette section 18 secured to shoulder saddle 5 by staples 19 and rivets 20, all as shown best in Figure 2. It will also be seen from said Figure 2 that the rubber filler 17 likewise has an off shoulder extension 17^a sloped to have a curved edge to match with the curved edges of elements 10^a and 18, thus further to constitute the epaulette section 18 an extremely efficient protective structure. In order further to increase the protective function of the epaulette section, the same includes, as its uppermost sheet element, a comparatively stiff or plate-like leather sheet 21. This sheet 21 is upwardly dished to have a transversely as well as a longitudinally arched chamber for the accommodation of a resilient metal strip member 22

positioned laterally of the chamber and anchored therein at opposite ends by means of rivets 20.

The epaulette section thus described consequently provides primarily a protective structure of a highly efficient character, due to the regularly diminishing resistance to deformation of its various components as one component lies below another, from the thick plate-like leather cap 18 to the bottom sponge rubber foundation 18^a. Nevertheless, such leather cap is deformable to some extent, when required, as indicated by the dot and dash lines marked 18' in Figure 2; to coact with and supplement the action of the rubber extension 18^a.

Referring now to the device 23, which may be defined as a shoulder joint protector, the same is clearly shown in Figures 1 and 2. This device fits over the joint between the upper arm and the shoulder and is shaped somewhat like the quarter of a hollow sphere. A suitably shaped pad 24 of felt is secured to a fairly stiff leather cap 26, shaped similarly to the felt pad but somewhat smaller, by the line of stitching, indicated at 27 in Figure 1, and applied to the marginal portions of the cap. Marginal portions of the felt pad may project beyond the cap all around the joint-protecting and shoulder-guard-positioning device 23.

In order to adapt said device 23 for action as described, the same is hingedly connected to the off-shoulder end of main portion 5 of the new guard, by a leather hinge shown at 28 in Figure 2; and the device has suspended therefrom, as by means of short tapes 29, a strap or loop 30. The arm of the player is pushed through this loop in donning the new guard; the bight of the loop traversing the arm-pit of the player when the guard is properly positioned on his body. The tapes 29 at their upper ends extend through slots in the leather cap 26 and are suitably secured to such cap as by rivets 25. The portions of the tapes which fall outwardly of said slots are entered in the opposite ends of strap 30, which is tubular and riveted as shown at 31 in Figure 1. The leather sheet or strip forming the hinge 28 is connected as shown in Figure 2, having one end tucked in between rubber sheet 17 and felt pad 14, and stitched to said pad, and having its opposite end tucked in between leather cap 26 and felt pad 24, and stitched in place as thus tucked.

Due to the flexible character of the hinge 28, and the presence of the extension 18^a, the structure 23 is very freely adjustable, and self-adjustable, to adapt itself for a close fit about the outer end of the shoulder and the upper end of the arm, regardless of the anatomical peculiarities of different individuals and despite the relative stiffness of the epaulette section 18. See in this connection

the dot and dash line indicated at 23^a, and the broken line indicated at 23^b in Figure 2.

I claim:

1. In a shoulder guard, the combination of a main over-shoulder portion, and an off-shoulder extension including a resilient cushion extended from the first mentioned portion, a substantially stiff but resilient epaulette overlying such extension, and a shoulder cap underlying said extension and hingedly connected to the first-mentioned portion.

2. A shoulder guard comprising a top shoulder portion and breast and back flaps flexibly connected thereto, a layer of felt forming the outer-surface or base of all of said portions, horizontal parallel slightly spaced strips of sponge rubber overlying the felt layer in said breast and back flaps, a continuous sheet of sponge rubber overlying the felt in the top shoulder portion, and an outer covering of leather overlying the sponge rubber strips and sheet and having portions depressed between said strips and secured by stitching passing through the felt layer, said sponge rubber sheet having an integral outward extension overlying the shoulder joint, and a shoulder joint guard of cupped formation hingedly connected to said top shoulder portion substantially under the base of said extension so that the extension overlies and protects the joint between the upper shoulder portion and the shoulder joint guard, and an upwardly convex leather cap of substantial stiffness overlying said extension and an adjacent part of said main shoulder portion.

3. A shoulder guard comprising a top shoulder portion and breast and back flaps flexibly connected thereto, a layer of felt forming the outer-surface or base of all of said portions, horizontal parallel slightly spaced strips of sponge rubber overlying the felt layer in said breast and back flaps, a continuous sheet of sponge rubber overlying the felt in the top shoulder portion, an outer covering of leather overlying the sponge

rubber strips and sheet and having portions depressed between said strips and secured by stitching passing through the felt layer, said sponge rubber sheet having an integral outward extension overlying the shoulder joint, a shoulder joint guard of cupped formation hingedly connected to said top shoulder portion substantially under the base of said extension so that the extension overlies and protects the joint between the upper shoulder portion and the shoulder joint guard, and an upwardly convex leather cap of substantial stiffness overlying said extension and an adjacent part of said main shoulder portion.

4. A shoulder guard comprising a top shoulder portion and breast and back flaps flexibly connected thereto, a layer of felt forming the outer-surface or base of all of said portions, horizontal parallel slightly spaced strips of sponge rubber overlying the felt layer in said breast and back flaps, a continuous sheet of sponge rubber overlying the felt in the top shoulder portion, an outer covering of leather overlying the sponge rubber strips and sheet and having portions depressed between said strips and secured by stitching passing through the felt layer, said sponge rubber sheet having an integral outward extension overlying the shoulder joint, a shoulder joint guard of cupped formation hingedly connected to said top shoulder portion substantially under the base of said extension so that the extension overlies and protects the joint between the upper shoulder portion and the shoulder joint guard, and an upwardly convex leather cap of substantial stiffness overlying said extension and an adjacent part of said main shoulder portion.

In testimony whereof I affix my signature.

ROBERT THOMAS MULLINS.
